UNITED STATES PATENT OFFICE

PAUL SCHMIDT, OF MUNICH, GERMANY

CONVEYING LIQUIDS AT HIGH PRESSURE BY MEANS OF EJECTORS

Application filed August 14, 1930, Serial No. 475,303, and in Germany August 21, 1929.

Ejectors are, in general, only used for the production of reduced pressures, for example, for the draining of trenches or cellars, for the emptying of vessels and the like, using water under pressure, is taken from the water mains. The height of delivery, in such cases amounts only to a few metres, whereas the driving pressure of the pressure liquid amounts to several atmospheres.

10 Experimental investigation of the pressures set up by ejector pumps for the production of high pressures it has now been found that hydraulic advantages can be obtained by dividing the driving fluid up into 15 separate streams and delivering these streams in succession to the flowing liquid to be delivered. The value from the hydraulic and commercial standpoints of the improvement obtained becomes more particularly manifest 20 when the driving pressure of the pressure liquid amounts only to a fractional part of the total height to which the liquid to be delivered is raised. By "driving pressure" as that term is used in connection with the present invention, is meant the working pressure, or 25 head that is to say, the difference of pressure between the inlet and outlet of the pressure liquid to and from the machine.

The invention, therefore, relates to the delivery of a liquid at high pressure by means of ejectors and its subject matter consists in subdividing the driving liquid into separate streams and delivering these streams in succession to the flowing liquid to be delivered. 35 For low delivery heights the use of an ejector according to the present invention is less advantageous, because when the driving liquid is supplied in the manner according to the present invention the cost of working the 40 pump is considerably increased. At low heights of delivery the amount of work to be done is, however, too small in relation to the cost of the hydraulic improvement to be made to pay. The circumstances are different when 45 greater delivery heights, amounting, for instance to several hundreds of metres, are required, because, in this case, the degree of efficiency of the pump assumes far greater importance. When delivery heights of about 50 one thousand metres and more are involved

the pump efficiency exerts an absolutely decisive influence.

Within the sphere of usefulness of the ejector pump according to the present invention there comes, for example, the feeding of high pressure vessels with a pasty mixture of fine-grained contact substance and heavy oil for the synthetic production of benzine. For this purpose the ejector is driven with pre-heated oil under pressure, which oil is to be 60 subjected to hydrogenation. In the more recent processes in the chemical industry which are worked at high pressures and in most cases with a pulverulent contact substance, there are other spheres of usefulness which 65 are substantially similar to those for the production of light oil. A particularly wide range of application of the process according to this invention is, however, the raising of oil from very deep bore holes. When the invention is used for this purpose it is advantageous to arrange the supply of the driving liquid to accord with the extension of the pipe.

An ejector apparatus suitable for this purpose is diagrammatically shown in the drawing in section along the longitudinal axis.

This apparatus comprises a pipe 1 for the pressure liquid and a pipe 2 for the liquid to be raised. The mixture of the pressure liquid under which the liquid to be raised is effected by means of ejector nozzles 3, 4, 5, 6, 7 and 8. The part of the apparatus worked by the nozzles 7 and 8 has a particularly advantageous action, because a retardation of the flow of the liquid through the apparatus is obtained in front of each of these nozzles by an enlarged part of the pipe 2 and consequently an increase of pressure is produced. 80 This increase of pressure may be obtained with a suitably modified construction, for example, by an eddy flow ($c_{wir} = a$ constant) of the liquid. This advantageous gain in pressure by the retardation of the flow of the liquid may obviously be extended to the whole of the ejector apparatus with the exception of the part in front of the first nozzle 3. In addition to this the several pressure nozzles 85 may be arranged at any desired distance 90 apart determined as suitable by the local con-

ditions. When the apparatus is built into a bore hole the advantage secured thereby is that only a fractional part of the driving liquid needs to be taken down to the lowest point of the conveying pipe, the remaining portion being tapped off at lesser depths from the pressure pipe. This arrangement of the ejector nozzles distributed over the whole depth of the bore hole naturally results in a reduction of the necessary cross sections and an economy in pipe losses.

What I claim is:—

1. The method of creating a high liquid pressure in a conduit which comprises admitting a liquid under low pressure into the conduit, and successively imparting to it, during its passage through the conduit, increments of pressure totaling the differential between said high and low pressures by impulses from individual jets from a single column of a liquid under a pressure less than the said high pressure to be created.

2. The method of creating a high liquid pressure in a conduit which comprises admitting a liquid under low pressure into the conduit, and successively imparting to it, during its passage through the conduit, impulses from individual jets of a pressure liquid which is under a pressure such that the difference of pressure between the inlet and outlet of the pressure liquid to and from the conduit is less than the high pressure to be created.

In testimony whereof, I have affixed my signature.

PAUL SCHMIDT.
